UNITED STATES PATENT OFFICE.

VAN D. SIPES, OF EMMETT, KANSAS.

BROODER HEATER.

Application filed January 25, 1927. Serial No. 163,465.

This invention relates to means for heating brooders and it has for its object the provision of a simple apparatus whereby water may be heated in an economical manner and caused to circulate through the brooder to maintain the desired temperature of the same. The invention also seeks to provide means whereby the supply of water will be automatically maintained to compensate for evaporation, and it is also an object of the invention to provide a compact structure to accommodate the circulating heating water and furnish means whereby the expansion of the water when heated will be accommodated. The invention is illustrated in the accompanying drawings and consists in certain novel features which will be hereinafter first fully described and then particularly pointed out in the appended claim.

In the drawings:

Figure 1 is an elevation of my improved heating apparatus;
Fig. 2 is a plan view of the same;
Fig. 3 is a sectional elevation of the expansion tank and the means for automatically maintaining the supply of water;
Fig. 4 is an enlarged detail section through the float controlled valve, and
Fig. 5 is an enlarged detail perspective view of the valve.

In the drawings, the reference numeral 1 indicates a portion of a chicken house or compartment and 2 indicates a brooder which is located within the said house or room, these parts being of any approved construction.

In carrying out the present invention, there is provided an expansion tank 3 and a reservoir or supply tank 4 which is located above the expansion tank and is equipped with a discharge pipe 5 leading to a point over the top of the expansion tank whereby the water will be permitted to flow from the reservoir into the expansion tank in the operation of the apparatus. Upon the discharge end of the pipe 5 is secured a valve cage 6 having a port 7 through which the water may escape and containing a valve 8 which is adapted to close the said port when the water in the expansion tank is at the predetermined level. This valve includes a closing member 9 which is substantially circular in cross section and of a diameter to fit closely to or within the port 7 when the valve is raised so that the flow of water

through the port will be prevented. Below the closing member 9, the valve is constructed with guides 10 and 11 which have portions of their margins arranged to slidably engage the walls of the valve cage and other portions, as indicated at 12, cut away to permit the water to pass the guides and flow into the expansion tank. The closing member 9 and the guides are all carried by a stem 13 which depends through the cage and may project below the lower end thereof in position to be engaged by the top of a float 14 which is provided within the expansion tank. The float may be of any well-known approved form and is sufficiently buoyant to follow the level of the water in the expansion tank as the same rises and falls. On the top of the float is provided a guide cage 15 which fits around the lower portion of the discharge pipe 5, as shown most clearly in Fig. 4, so that the float will be guided in its movements and will always be in proper operative relation to the valve. The cage 15 should have sufficient frictional engagement with the surface of the pipe 5 and the valve cage 6 to prevent the float being dislodged from the pipe and this result is further attained by extending the guide cage above the flange 16 of the valve cage or casing so that the down movement of the float will be arrested by the upper end of the guide cage impinging upon the top of the said flange. It will now be understood that, when the water in the expansion tank is at a high level, the float will be raised so that it will impinge against the lower end of the valve stem 13 and will carry the valve into proper engagement with the port 7 so that the flow of water into the expansion tank will be arrested. Should the level of the water in the expansion tank fall by reason of evaporation to a perceptible extent, the float will, of course, descend and the valve will then unseat through its own weight, permitting the water to flow from the reservoir into the tank, the flow being cut off by the return rising movement of the float as the tank fills. The valve casing is, of course, provided with a stop 17 near its lower end to prevent the valve dropping from the casing.

Communicating with the interior of the expansion tank at or near the bottom thereof is a circulating pipe 18 which extends upwardly and laterally into a heating tank 19 which is intended to rest directly upon

the top of a heater, indicated by dotted lines at 20. The heater may be of any approved construction and I have employed an ordinary oil-burning cook stove, the legs being removed to reduce height. The tank 19 is of less capacity than the expansion tank and will always be completely filled with water. A circulating pipe 20 leads from the end of the tank 19 remote from the pipe 18, and this pipe 20 enters the brooder 2 and within the brooder is carried back and forth to form a heating coil 21, a pipe 22 connecting the coil with the expansion tank near the top of the latter.

15 It is thought the operation will be readily understood from the foregoing description, taken in connection with the accompanying drawings. The expansion tank being filled to such a height that the flow-

20 controlling cut-off valve 8 is seated, the entire circulating system including the heating tank 19, the pipes 18, 20 and 22 and the coil 21 will be filled with water, it being noted that the float and valve are ar-

25 ranged to operate at a point above the point of communication of the pipe 22 with the expansion tank. The heat from the stove will play directly upon the tank 19 and the water in said tank will thereupon be raised

30 in temperature so that it will flow through the pipe 20 into the coil 21 and thence back and forth to eventually reach the return pipe 22 and thereby flow again into the expansion tank. Inasmuch as the entire coil

35 21 and the greater portion of the circulating system is within the brooder, the brooder will obtain the benefit of the heat radiated from the said parts and may be easily maintained at the desired temperature.

40 The heat acts directly against the bottom of the heating tank, and the pipe 18 delivering water to said tank will preferably be connected therewith at a higher level than the pipe 20 leading water therefrom so that the natural flow of the water will be into and through the parts of the system which are located within the brooder.

45 The water, of course, will lose heat as it

circulates through the pipes 20 and 22 and the coil 21 but when it returns to the expansion tank it will still be at a higher temperature than when it left the tank originally. Gradually the water in the expansion tank will acquire a perceptible degree of heat so that a very slight consumption of fuel will be needed to maintain the temperature of the water in the circulating system. The top of the tank 3 is open so that the expansion of the water due to the heating thereof will be accommodated but some of the water will evaporate under the influence of the heat acquired thereby and eventually there will be such a lowering of the body of water in the expansion tank that the float will descend and the valve will be opened, cold water being then permitted to enter the tank to replenish the supply. It will thus be seen that I have provided a very simple and compact apparatus which may be operated very economically to maintain the proper temperature in the brooder and the supply of water in the circulating system will be automatically maintained, it being necessary to supply additional water to the reservoir 4 only at long intervals.

Having thus described the invention, I claim:

A brooder heater comprising a stove arranged adjacent the brooder, a flat shallow heating tank resting directly on the stove, an expansion tank arranged at one side of the heating tank and the stove with its bottom below the plane of the heating tank; a pipe leading from the expansion tank near the bottom thereof into one side of the heating tank, a circulating pipe leading laterally from the opposite side of the heating tank straight into the brooder, a coil within the brooder connected to and in communication with said pipe, and a return pipe connected to and leading from said coil into the upper portion of the expansion tank.

In testimony whereof I affix my signature.

VAN D. SIPES. [L.S.]
